FLUORESCENT SIGN LAMP

Paolo Sereno, Rome, Italy

Application April 20, 1949, Serial No. 88,620

4 Claims. (CL 40—134.1)

1

This invention relates to signs, and, more particularly, is concerned with fluorescent sign lamps.

Even more specifically, the present invention pertains to that type of fluorescent sign lamp wherein the sign comprises a plurality of letters, characters and/or symbols (all hereinafter referred to as "characters") fashioned from fluorescent material and carried by an elongated plate of insulating material which is located within a transparent tube. The tube is filled with rarefied gases and is arranged to pass an electric discharge which activates the fluorescent material of the characters. Signs of this type conventionally have the characters formed by tracing the same with fluorescent powders on the elongated plate.

In present-day manufacture of signs of the character described, many difficulties are present which have made the signs delicate, expensive and complicated. The principal difficulties have been: failure to obtain a clean and uniform tracing of the characters on the elongated plate, unsatisfactory mounting of the elongated plate in the transparent tube, special care in handling the various components during manufacture, inability to secure a simple and firm assembly of the parts in the completed sign, and complicated devices to direct the electrical discharge and obtain a sufficient intensity of light emanation from the fluorescing characters.

It is an object of my invention to provide a fluorescent sign lamp wherein the foregoing difficulties are overcome.

It is a more specific object of my invention to provide a fluorescent sign lamp of the character described in which the characters can be traced quickly and easily by filling in shallow depressions of proper outline so that the finished characters are clean and uniform.

It is another specific object of my invention to provide a fluorescent sign lamp of the character described wherein the plate is indirectly supported by the tube thereby to obtain a firm and quickly assembled plate mounting which will not cause breakage of the fragile tube and plate during either construction or use.

It is another specific object of my invention to provide a fluorescent sign lamp of the character described wherein the plate mounting constitutes resilient members and cushions so that, although the mounting is firm, the plate, nevertheless, will not exert any sudden or substantial pressure against the tube.

It is another specific object of my invention

2

to provide a fluorescent sign lamp of the character described wherein the plate is so positioned in the tube that the full electrical discharge passes in front of the plate so that a hitherto unobtained degree of brilliance is attained by the fluorescent characters.

Other objects of my invention will in part be obvious and in part will be pointed out herein-after.

10 My invention accordingly consists in the features of construction, combinations of elements and arrangements of parts which will be exemplified in the constructions hereinafter described and illustrated and of which the scope of application will be indicated in the appended claims.

In the accompanying drawings in which are shown various possible embodiments of my invention,

20 Fig. 1 is a front view of a fluorescent sign lamp constructed in accordance with my invention;

Fig. 2 is an enlarged axial section through one of the ends of the sign in a plane perpendicular to the character-carrying plate;

25 Figs. 3 and 4 are sectional views taken substantially along the line 3—3 and 4—4, respectively, of Fig. 2;

Fig. 5 is a broken-away perspective view of the end of the sign shown in Fig. 2; and

30 Figs. 6 and 7 are transverse sectional views through ends of fluorescent sign lamps having modified forms of plate mountings embodying my invention.

Referring now in detail to the drawings, and, more particularly, to Figs. 1 through 5, the reference numeral 10 denotes a fluorescent sign lamp embodying my invention. Said lamp comprises an elongated transparent tube 12 which, conventionally, is fabricated from glass and is of circular cross-section, it being understood that

40 the particular configuration of the cross-section can be varied to suit consumer demand. Both ends of the tube are tapered to hermetically closed stems 14. The tube is evacuated through a stub 16 which subsequently is sealed. Before sealing, however, the tube is charged at a conventional pressure with one or more of the rare gases which commonly are used in standard fluorescent lamps. By way of example argon or

45 krypton may be employed at a pressure of between 0.5 to 2 mm. of mercury. In addition a small amount of mercury vapor can be present.

At the ends of the tube I provide the usual electrodes 18 mounted on lead-in wires 20 which are conventionally sealed in the stems. The electrodes are shown as representative either of

the "cold" electrode type, operating with a high voltage drop and a high striking voltage, or of the oxide-coated heated electrode type, operating with a low voltage drop and starting with a comparatively low striking voltage. As is well understood, both types are suitable for the purpose of maintaining an electric discharge in an attenuated gas. For example, elongated cylinders of nickel or iron, coated with barium oxide, may be used as electrodes. The lead-in wires run to terminals 22 which, as illustrated, may be of the type adapted to be plugged in suitable sockets. Energy is supplied to the electrodes through any conventional circuit. The ends of the tube are housed in shells 24 which, conveniently, are made from a plastic, e. g. a phenol formaldehyde condensation resin. The tubes are secured to the shell, for example by cement 26, and openings are provided for passage and support of the terminals 22.

Located within the tube 12 and extending over substantially its entire length, is a plate 28 which, desirably, is made of an electric insulating material, e. g. glass. The plate has a breadth which is somewhat smaller than the inside diameter of the tube. Pursuant to a principal feature of my invention, the plate is offset from the longitudinal axis of the tube. In other words, the plate, which is thin and has parallel, plane front and back surfaces, and, moreover, which is arranged with said surfaces parallel to this axis of the tube, has its front surface spaced from said axis in a direction radially of the tube and its rear surface located on the same side of said axis. It is on this front surface of the plate that the fluorescent characters are carried, so that said characters face the major portion of the tube space through which the electric discharge between the electrodes passes. I have found that such an arrangement results in an appreciable increase in brilliance compared to an arrangement in all respects similar save for the aforesaid placement of the plate, such plates heretofore having been located so as to include the longitudinal axis of the tube.

Means is provided to hold the plate in its stated position. As shown in Figs. 1 through 5, said means comprises a spring plate ring 30 compressed between the tube and the plate, one such ring being provided at each end of the plate. To avoid contact of the plate with the tube, each end of the plate is wrapped in a ribbon 32 which is yielding and, preferably, is electrically non-conductive and a poor heat conductor. Examples of materials of this nature are asbestos and glass fiber ribbons. By way of illustration, the ribbon is 20 mm. wide and about 2 mm. thereof is permitted to extend beyond the edge of the plate. One turn with some overlap (see Fig. 5) is wrapped about each end of the plate before the plate is inserted in the tube.

The ring 30 can be simply made from a flat strip of spring steel provided with a notch on each edge thereof near its ends. The notches are on opposite longitudinal edges and have depths equal to approximately half the width of the strip. The strip is bent to overlap its ends and register the notches, and the latter are interengaged to fix the ring in an approximately circular shape. The ring then is compressed and inserted between the tube and plate. Contact between the ring and tube is avoided by wrapping the junction of each ring with a ribbon 34 similar to the ribbon 32 and placing said wrapped

junction adjacent the tube. After the ring is released, it will press its associated end of the plate against the tube and firmly and resiliently hold it in position, the ribbons serving to cushion any shock experienced during assembly or use. A further advantage of this construction is that it permits expansion of the parts during the heating incident to obtaining a vacuum, and also allows large tolerances and slight movements of the parts without causing breakage because of the imposition of sudden or substantial stresses on the delicate tube. Other rigid mounting systems that will not permit movements, or will allow parts to come into contact at different temperatures or because of different heat conductivity characteristics, will result in breakage.

The ring functions to hold the plate against transverse movement. Means also is included to hold the plate against longitudinal movement. Such means comprises a nub 36 near each end of the tube and at an end of the plate 28. Said nubs are formed by locally heating the tube at the desired regions until the tube softens and then indenting the tube with a blunt rounded point. This operation is performed after the plate is in the tube and the nubs thus are pressed against the ribbons 32.

The characters are provided by forming shallow depressions 38 of proper outline in the plate 28 and filling the depressions with a fluorescent material 40. The depressions are fashioned in any suitable manner, for instance by sand-blasting through a stencil, chemical etching, photo-engraving or molding when the plate is made. Over the area of the plate thus treated there is applied, as by brushing or spraying, fluorescent powders in suspension in a varnish, lacquer or other suitable fluid carrier of the type commonly used for the application of such powders on glass tubes. If desired, powders of different composition can be employed on different areas of the plate in order to obtain differently colored characters when the tube is activated. After the carrier is dry, the front surface of the plate is scraped with a straight edge to remove all fluorescent powder except that inside the depressions. Then the plate is heated to volatilize the solidified carrier, as is done in the manufacture of fluorescent lamps. By way of example, a satisfactory depth for the depressions is about 0.5 mm. It will be apparent that the formation of the characters is carried out before insertion of the plate in the tube.

It is desired to point out that, when the depressions are formed by actual removal of portions of the plate, i. e. by etching, the surface to which the powders are applied can be thoroughly cleaned and there is no likelihood that the powders will fall off during use, as now often is the case, because the surfaces to which the powders are applied cannot be kept perfectly clean while manufacturing the plate.

It may be mentioned that the sequence of steps in the assembly of the sign is to insert the prepared and wrapped plate in the tube, place the rings in position, form the nubs, insert the electrodes, form the stems, evacuate the tube, charge the tube, close the stub, connect the terminals, apply the shells, and mount the terminals.

In Fig. 6 I have shown a fluorescent sign lamp 42 which is similar in all respects to the lamp 10 except for the means to hold the character plate against transverse movement. All parts identical with parts of the lamp 10 are denoted by the same

reference numerals primed. The plate 28' is held against transverse movement by a two-ended compression spring 44 having a loop 46 intermediate its ends. Refractory beads 48, 50, e. g. ceramic beads, are mounted on the ends of the spring. One bead bears against the inner surface of the tube 12' and the other against the plate 28', the latter bead pressing either directly against the plate or engaging the ribbon 32'. To hold the spring in place, the tube 12' is heated in the region of the bead 48. When the tube softens slightly this bead will push out the wall a short distance to form a depression 52 in which the bead 48 remains seated.

The foregoing plate mountings are resilient; however, in accordance with another aspect of my invention the character plate is rigidly mounted, this form of the invention being illustrated in Fig. 7 wherein all parts similar to those of the lamp 10 are denoted by the same reference numerals double primed. The sign 54 shown in Fig. 7 has its character plate 28'' held in offset position by a pair of mounting members 56, one at each end of the plate. Each such member comprises a small rod 58 having branching arms 60, 62 on an end thereof, so that the member is approximately in the shape of a Y. On the rod 58, i. e. the shank of the Y, a notch is provided which engages or fits into a corresponding notch on the associated end edge of the plate 28'', so that, with its two ends thus supported, the plate is rigidly held in the tube. To keep the mounting members in place, each of the ends of the Y is fashioned with an indentation into which the wall of the tube after softening, for instance by the application of heat, is pushed, the resulting configuration being clearly indicated in Fig. 7. If desired, a thin ply of asbestos or glass wool ribbon may be inserted between the members 56 and ends of the plate 28'' to discourage rocking of the plate. It will be observed that in this form of my invention the character plate does not touch the tube and accordingly it is not necessary to interpose any cushioning element between said plate and tube.

It thus will be seen that I have provided signs which achieve the several objects of my invention and are well adapted to meet the conditions of practical use.

As various possible embodiments might be made of the above invention, and as various changes

might be made in the embodiments above set forth, it is to be understood that all matter herein described, or shown in the accompanying drawings, is to be interpreted as illustrative and not in a limiting sense.

Having thus described my invention, I claim as new and desire to secure by Letters Patent:

1. A fluorescent sign lamp comprising a sealed elongated transparent tube, electrodes adjacent opposite ends of said tube, a charge of attenuated gas in said tube, a plate in said tube, said plate having fluorescent characters on a surface thereof, the width of said plate being less than the major cross-sectional dimension of the tube, and means to locate said plate in a position offset from the central longitudinal axis of the tube with its character-carrying surface extending longitudinally of the tube and radially spaced from said axis and the opposite surface of the plate disposed on the same side of the axis and spaced further therefrom.

2. A fluorescent lamp sign as set forth in claim 1 wherein the locating means comprises a resilient member under compression between the character-carrying surface of the plate and the opposite wall of the tube.

3. A fluorescent lamp sign as set forth in claim 1 wherein the locating means comprises a resilient member under compression between the character-carrying surface of the plate and the opposite wall of the tube and a cushioning element disposed between the opposite surface of the plate and the adjacent wall of the tube.

4. A fluorescent lamp sign as set forth in claim 1 wherein the locating means comprises a spring ring under compression between the character-carrying surface of the plate and the opposite wall of the tube.

PAOLO SERENO.
